UNITED STATES PATENT OFFICE

138,206

DESIGN FOR AN ABRASIVE CUTOFF MACHINE

Robert S. Condon, Rutland, Vt.

Application February 25, 1944, Serial No. 112,701

Term of patent 14 years

(Cl. D37—1)

To all whom it may concern:

Be it known that I, Robert S. Condon, a citizen of the United States, residing at Rutland, county of Rutland, State of Vermont, have invented a new, original, and ornamental Design for an Abrasive Cutoff Machine, of which the following is a specification, reference being had to the accompanying drawings, forming a part thereof.

In the drawings:

Fig. 1 is a front elevation of an abrasive cutoff machine showing my new design.

Fig. 2 is an elevational view of one side thereof.
Fig. 3 is an elevational view of the other side thereof.

Fig. 4 is a top plan view thereof.

Fig. 5 is a rear elevational view thereof.

I claim:

The ornamental design for an abrasive cutoff machine, substantially as shown.

ROBERT S. CONDON,
